UNITED STATES PATENT OFFICE.

HARRY R. COREY, OF BROOKLYN, NEW YORK, ASSIGNOR TO AMERICAN STOPPER COMPANY, OF BROOKLYN, NEW YORK, A CORPORATION OF NEW JERSEY.

DESIGN FOR A SHEET-METAL TALCUM-CANISTER.

46,333.

Specification for Design.

Patented Sept. 1, 1914.

Application filed December 30, 1912. Serial No. 739,416. Term of patent 7 years.

To all whom it may concern:

Be it known that I, HARRY R. COREY, a citizen of the United States, residing at No. 519 Fifth street, Brooklyn, Kings county, New York, have invented a new, original, and ornamental Design for a Sheet-Metal Talcum-Canister, of which the following is a specification, reference being had to the accompanying drawing, forming a part thereof.

In said drawing, Figure 1 is a perspective view of a sheet metal talcum canister showing my new design and Fig. 2 is a plan view of the same.

The design comprises a body rectangular in cross section, tapering from the base upward and formed with rounded inclined cor-

ners. This body is terminated at the bottom by an outwardly extending bead, and is terminated at the top by an outwardly extending bead. Above the top bead the canister is continued vertically upward for a short distance and is formed with rounded corners. In the middle of the extreme top is located an upwardly extending cylindrical neck, terminating in a circular cap.

I claim:

The ornamental design for a sheet metal talcum canister, as shown.

HARRY R. COREY.

Witnesses:

W.M. J. MACHESKI,
J. L. CANNOLD.
